HARRISON O. PARKER, OF TULSA, OKLAHOMA, ASSIGNOR TO THE MATHIESON ALKALI WORKS, OF NEW YORK, N. Y., A CORPORATION OF VIRGINIA.

REFINING OILS.

Application filed January 22, 1925. Serial No. 3,983.

This invention relates to the refining of hydrocarbons, and includes an improved method of refining hydrocarbon oils and distillates, particularly light petroleum oils, such as gasoline, and especially casinghead gasoline and natural gas gasoline. The invention also includes an improved apparatus for carrying out the process of the invention.

When gasoline containing substantial amounts of hydrogen sulfide gas or of other unstable sulfur compounds is stored for some time, these sulfur compounds tend to decompose, perhaps by slow and partial oxidation, with the formation of elemental sulfur which is dissolved in the oil. This dissolved sulfur makes it very difficult satisfactorily to refine the oil after such decomposition occurs. Casinghead gasoline and natural gas gasoline, moreover, have very high vapor pressures, and to prevent unnecessary evaporation losses it is desirable to put such products into permanent storage as quickly as possible after production. In many instances, particularly in the case of isolated plants, the production of casinghead gasoline or of natural gas gasoline while continuous is at a relatively low rate, and it has been customary temporarily to store such products as produced and periodically to refine the stored material because the continuous methods of treatment available have been inefficient and uneconomical when employed on a small scale. For example, it has hitherto been proposed to refine hydrocarbon oils with aqueous solutions containing hypochlorites. The methods commonly practiced, however, are usually carried out as batch operations and ordinarily involve the separate preparation of the hypochlorite solutions from liquid chlorine or from bleaching powder or in some other suitable way. Where such refining operations have been carried out in a continuous manner, it has been necessary separately to prepare and to store the hypochlorite refining solutions employed.

According to the present invention, the oil to be refined is subjected to treatment with an aqueous hypochlorite solution initially containing a considerable excess of a caustic

alkali, such as caustic soda, and sufficient chlorine is introduced into the solution, as the refining operation continues, to maintain a concentration of hypochlorite therein sufficient to effect the desired refining treatment. As the caustic alkali is used up it is replaced or replenished so that the refining operation may be carried out in a substantially continuous manner.

The separate preparation of the hypochlorite refining solution is thus eliminated, and any necessity for storing the hypochlorite solution is also avoided. Chlorine is readily available and easily handled as a liquid stored under pressure in steel cylinders and the present invention is particularly advantageous, where liquid chlorine is utilized. The chlorine may be introduced directly, in properly regulated amounts, into the alkaline aqueous solution and after introduction the chlorine combines with the caustic alkali therein to form the corresponding hypochlorite. Chlorine gas, however, may be employed for introduction into the alkaline aqueous solution to form a hypochlorite therein.

Gasoline products, and particularly the lighter and more volatile gasoline products, may thus be refined and desulfurized by treatment with a hypochlorite solution in a continuous way, avoiding any decomposition incident to storage of the unrefined oil and avoiding evaporation losses due to temporary storage of the oil before refining. Where the oil to be refined contains appreciable quantities of hydrogen sulfide or other undesirable constituents which will react with caustic alkali, the oil may be subjected to preliminary treatment with an aqueous alkaline solution, such as a solution of caustic soda, to promote economy of the hypochlorite refining solution, and this treatment may also be carried out in a continuous manner. The method of the present invention is of special value and application where the production of the oil is continuous but at a relatively low rate, and enables the efficient and economical application of hypochlorite refining solutions in a continuous manner in such instances.

The apparatus of the invention may comprise a series of three towers through which the oil to be refined is successively passed as a flowing stream, means being provided for forcing the oil into the lower end of the first tower and connections being arranged to conduct the oil from the top of the first tower to the bottom of the second and from the top of the second to the third and to discharge the oil from the top of the third. The first two towers are charged with the refining solutions and the oil is contacted therewith as it rises through the towers. The towers in which the preliminary alkali treatment and the hypochlorite refining treatment are carried out are provided with connections for introducing fresh caustic alkali solutions and for discharging the spent solutions. The tower in which the hypochlorite refining treatment is effected is provided with means for introducing chlorine and for distributing it through the alkaline solution in the tower. The chlorine is advantageously supplied from a container of liquid chlorine under pressure and the amount of chlorine introduced can advantageously be determined for purposes of control by arranging the liquid chlorine container on scales and by weighing the amount of chlorine introduced. The third tower acts as a settling tower for the separation of any refining solution which might be carried along with the oil.

The invention will be further described in connection with the accompanying drawing which illustrates an apparatus embodying the invention and adapted for carrying out the process of the invention, but it will be understood that this further detailed description and illustration are for the purpose of exemplification and that the invention is not limited thereto. The general arrangement of apparatus illustrated in the drawing is of general utility in carrying out the process of the invention. The specific apparatus described in detail in connection with the drawing, however, is well adapted for the treatment of about 100 bbls. of gasoline per hour.

Referring to the drawing, the apparatus there illustrated comprises three vertical towers, A, B and C, about four feet in diameter and 18 feet high, of either welded or riveted construction and tested to about 75 lbs. pressure. The first tower A is provided with a 2" pump-in line 1 entering the tower 8" from the base and passing through almost to the opposite side of the tower. The section of pipe inside the tower is provided with 18 cross slits each about 1 1/2" in length and about 1/8" across. From the top of the tower A a 3" overflow line 2 is arranged to discharge into the lower part of the second tower B. A connection 3 is provided for introducing fresh caustic alkali

solution into the tower and a connection 4 is arranged for discharging spent solution from the tower. A sample cock 5 is also provided in the overflow line 2. A 3" pipe 6 is arranged entering the second tower B 70 18" from the bottom and extending therethrough nearly to the opposite side for the introduction of oil into this tower. This pipe is connected to the overflow line 2 through valve 7 and to the pump-in line 8 75 through valve 9. Pump-in line 1 has valve 10 therein. Lines 1 and 8 are each connected to the pump 11 for forcing the oil to be refined through the towers and by appropriate control of the valves 7, 9 and 10 80 the oil may be forced through tower A to tower B or directly to tower B.

The pipe 6 for introducing oil into the tower B is provided with eighteen slits having a total area approximately half that of the slits 85 in line 1. A connection 12 is provided for introducing fresh caustic alkali solution into tower B and a connection 13 is arranged for discharging spent solution from the tower. An overflow line 14 is arranged for discharging oil from the upper end of the tower into the tower C. A sample cock 15 is provided in the line 14. A 1/2" extra-heavy perforated pipe 16 is arranged in the bottom of the tower B for the introduction 95 of chlorine. This pipe is connected to the liquid chlorine container 17 successively through a cast iron check valve 18, a cast iron globe valve or plug cock 19, a cast iron check valve 20, an expansion valve 21, an 100 expansion coil 22 and a needle valve 27 on the container 17. The liquid chlorine container 17 is arranged inverted in a frame 23 supported on a platform scales 24. The overflow line 14 is connected to a 3" perforated pipe 25 arranged about 6 ft. from the bottom of the settling tower C. An overflow line 26 is provided for discharging the refined oil from the upper end of the tower and a drain connection 27 is provided for removing any settled material from the lower end of the tower.

In refining a gasoline product according to the present invention in the apparatus illustrated, the tower A is charged with a 115 caustic alkali solution and the tower B is charged with a caustic alkali solution in which hypochlorite is formed by the introduction of chlorine. The tower A may be charged with a solution made up with about 120 800 gals. of water and about 700 to 725 lbs. of caustic soda. This solution may be made up by melting down solid caustic soda with steam in the usual way, adding the necessary volume of water, and cooling the solution to a temperature of from about 70° to 80° F. before introduction into the tower. The caustic alkali solution employed in the tower B may be of similar composition. Before starting the flow of gasoline through the 125 130

towers, chlorine is introduced into the tower B from the liquid chlorine container 17. Initially, about 50 lbs. of chlorine may be run in over a period of 30 minutes, and as the refining operation continues additional amounts of chlorine may be run in from time to time as required. The chlorine may be added without interrupting the refining operation. It is generally convenient and satisfactory to run in about 50 lbs. of chlorine at a time over a period of about 30 minutes. The amount of chlorine introduced is measured by the difference in weight on the scales 24. The chlorine is introduced by opening the needle valve 27 and the globe valve 19, and the flow is regulated by the expansion valve 21. Except during the periods when chlorine is being introduced, the needle valve 27 and the stop valve 19 are kept closed. In connection with a charge of the caustic soda solution of the amount and character just described it is convenient to employ cylinders containing about 150 lbs. of liquid chlorine. 800 gals. of the caustic soda solution described will absorb approximately 450 lbs., or three cylinders, of liquid chlorine when used in carrying out the refining process of the present invention.

After the towers A and B have been charged with the caustic alkali solution and after the introduction of the initial amount of chlorine into the solution in the tower B, the gasoline, or other oil, to be refined is pumped successively through the towers A, B and C. In the towers A and B the gasoline is sprayed through the treating solutions and intimately contacted therewith, pressure being maintained sufficient to force the gasoline through each tower and to distribute it through the treating solutions in the towers. The tower C gradually fills with gasoline and the refined gasoline product overflows through pipe 26. With a caustic soda solution of the amount and character previously described in tower A, the operation can usually be continued for several weeks before this solution needs to be replaced or replenished. A convenient test is to withdraw a portion of the gasoline from the test cock 5 and agitate it with a lead acetate solution. If a black precipitate appears the caustic alkali solution in tower A should be replaced or replenished. Chlorine is introduced into the caustic alkali solution in tower B from time to time as required to produce a sweet product. If a test sample withdrawn from the sample cock 15 gives a positive "doctor" test it indicates that additional chlorine is required. After about 450 lbs. of chlorine have been introduced into a caustic soda solution of the amount and character previously described, the solution is usually discharged and replaced with fresh solution. The caustic alkali content of the treating solution in tower

B may, however, be partially replaced from time to time.

Where the gasoline contains appreciable amounts of hydrogen sulfide or of other objectionable constituents which will react with caustic alkali, the gasoline is pumped first through tower A and thence to tower B, but, in the treatment of gasoline free from appreciable quantities of such constituents, the gasoline is pumped directly through tower B.

While the invention has been described particularly in connection with the treatment of gasoline, especially casinghead gasoline and natural gas gasoline, in which application it is of particular advantage, it will be apparent that the invention is of more or less general application in the treatment of hydrocarbon oils and distillates which are susceptible to refining treatment with aqueous hypochlorite solutions.

I claim:

1. An improved method of refining hydrocarbon oils in a continuous manner which comprises passing the oil through a body of aqueous hypochlorite solution containing an excess of caustic alkali, introducing chlorine into the solution in the proximity of the point at which the oil is introduced, whereby additional quantities of hypochlorite are formed and the oil is subjected to that portion of the solution containing the highest concentration of hypochlorite first.

2. An improved method of refining hydrocarbon oil in a continuous manner which comprises passing the oil through a body of aqueous hypochlorite solution containing an excess of caustic alkali, introducing fresh caustic into the solution to maintain the alkali in excess as the reaction progresses, and introducing chlorine at a point remote from that at which the alkali is introduced but in the proximity of the point at which the oil is introduced, whereby additional quantities of hypochlorite are formed and the oil is subjected to that portion of the solution containing the highest concentration of hypochlorite first.

3. An improved method of refining hydrocarbon oils in a continuous manner which comprises passing the oil through a relatively long column of aqueous hypochlorite solution containing an excess of caustic alkali, introducing fresh caustic at one end of the column to maintain the alkali in excess as the reaction progresses, introducing chlorine at the other end of the column nearest the point at which the oil is introduced, whereby the oil is subjected to that portion of the solution containing the highest concentration of hypochlorite first.

4. An improved method of refining hydrocarbon oils in a continuous manner which comprises passing the oil first through a column of caustic alkali solution, then pass-

ing the oil through a column of an aqueous hypochlorite solution containing an excess of caustic alkali, introducing fresh caustic alkali into one end of the hypochlorite column to maintain the alkali in excess as the reaction progresses, introducing chlorine at the other end of the column nearest the

point at which the oil is introduced, whereby the oil is subjected to that part of the solution containing the highest concentration of 10 hypochlorite first.

In testimony whereof I affix my signature.

HARRISON O. PARKER.
